UNITED STATES PATENT OFFICE.

FREDERICK H. EDWARDS, OF MERIDEN, CONNECTICUT, ASSIGNOR TO AMERICAN MANGANESE STEEL COMPANY, OF AUGUSTA, MAINE, A CORPORATION OF MAINE.

GYRATORY CRUSHER.

1,410,244.

Specification of Letters Patent. Patented Mar. 21, 1922.

Application filed December 31, 1920. Serial No. 434,213.

To all whom it may concern:

Be it known that I, FREDERICK H. EDWARDS, a citizen of the United States, and a resident of Meriden, in the county of New Haven and State of Connecticut, have made and invented certain new and useful Improvements in Gyratory Crushers, of which the following is a specification.

My invention relates to gyratory crushers, and more particularly to the crusher head.

The severe service to which the crusher head is necessarily exposed has heretofore caused the mantle to peen or stretch and accordingly become loose upon the core, which results in a further stretching or peening of the same and in some instances has allowed the mantle to turn with relation to the core and thus loosen the holding bolts or nuts by means of which the mantle is held in place. Further, the loosening of the mantle has allowed the jars and impacts to be transmitted to the locking rings and nuts and thus has, in time, mutilated and destroyed the threads upon the crusher shaft, rendering necessary the replacement of the entire crusher shaft.

It is accordingly an object of my invention to provide a crusher head which is so designed and arranged that the wearing mantle will always remain tight upon the core even though it peen and stretch in service and, remaining tight upon the core, will prevent any jars or impacts from being transmitted to or brought to bear upon the threaded portion of the crusher shaft.

A further object is to take advantage of the tendency of the wearing mantle to rotate with respect to the core by causing this tendency to rotation to force the mantle wedgedly against the core, thus holding the mantle firmly in place and preventing any hammering between the mantle and core, or between the mantle and the locking ring and nut.

A further object is to provide a locking ring which may be formed of manganese steel, which will abut against, and the surface of which will form a continuation of the surface of, the wearing mantle, and in connection with the locking ring to provide a lock nut which will not only hold the locking ring against rotation or movement but

will also center it with respect to the shaft and hold it out of contact with the latter, 55 the locking ring tending to protect the extremity of the wearing mantle and also the lock nut against injury during the operation of the crusher.

A further object is to attain the aforementioned ends in a simple and expeditious manner; the crusher head being so designed and arranged that, with the mantle once properly seated upon the core, it will always remain so fixed regardless of any stretching 60 or peening which it may experience in service, and also so constituted that the mantle will remain tightly secured in place regardless of the direction of rotation of the crusher shaft, thus doing away with the 70 present arrangement wherein it is necessary to provide a construction which is adapted to operate under a given condition as to the direction of rotation of the crusher shaft, and wherein serious losses have occurred 75 when a crusher head which was intended to operate in a mill which rotated in a clockwise direction was, through error and mistake, placed in a mill which operated in a counter-clockwise direction. 80

With the foregoing and other objects in view, my invention consists in the improved crusher head illustrated in the accompanying drawing and described in the following specification, and in the combination and arrangement of parts and in the details of construction as hereinafter described and claimed, it being understood that changes may be made within the scope of the claims without departing from the spirit of the invention. 90

The preferred embodiment of my invention is disclosed in the accompanying drawing, wherein:

Figure 1 is a view in elevation of my improved crusher head; and

Figure 2 is a somewhat enlarged view in vertical longitudinal section of the same and illustrating the structural details thereof.

Referring specifically to the several views 100 wherein similar reference numerals designate corresponding parts throughout, the crusher shaft 10 is provided with the usual threaded portion 11 and core 12. The core is permanently secured to or formed as a 105 part of the shaft 10 and is provided with

the external conical surface 13, the core and shaft as thus formed being of standard construction as in commercial use at the present time.

- 5 A wearing mantle 14, preferably formed of manganese or other wear-resisting steel, is provided with the inner conical surface 15 which is adapted to seat against and contact with the conical surface 13 of the core. In
10 order that the wearing mantle will, at all times, remain rigidly and wedgedly fixed to the core 12, even though it stretch and peen under the severe stresses to which it is necessarily exposed, I have provided the smaller
15 extremity of the mantle with a base 16 which lies in a plane extending at an angle to the axis of the conical shape mantle. This inclination of the base forms in fact two inclined surfaces 17, 18, which are adapted to
20 operate in the manner of a double ratchet and cooperate with the similarly inclined faces 19—20 of a locking ring 21. I do not wish to limit myself as to the number of inclined faces with which the locking ring
25 and wearing mantle may be provided, as it will be readily appreciated that the number may be increased without departing from the spirit of my invention.

The locking ring 21 is also preferably formed of hard wear-resisting metal, such as manganese steel, and is provided with the groove or annular recess 22, into which extends the ledge or shoulder 23 of a lock nut 24. The lock nut 24 threadedly engages the shaft 10 and is provided with holes (not shown) for engagement by a spanner wrench, or is provided with other similar artifice whereby the lock nut may be tightly screwed into place. A key 25 is
30 adapted to engage the shaft 10 and lock nut 24 and positively lock the two against relative rotation. In order that the locking ring may be positively fixed to the lock nut, I have provided the confronting surfaces of
35 the lock nut and locking ring with the semi-cylindrical recesses 26. A pin 27 is adapted to be forcibly driven into a pair of aligned recesses and thus positively lock the nut and ring against relative rotation.
40 With the parts as thus constructed the absence of threads on the locking ring 21 allows it, as previously mentioned, to be formed of manganese steel and the surface of the locking ring, extending flush with
45 the surface of the wearing mantle, prevents the local injury or abrasion of the latter and provides that the coating surfaces of the locking ring and mantle will always properly function to exert an end pressure
50 on the wearing mantle. Further, the lock nut is sharply bevelled away from the surface of the locking ring so as to prevent the lock nut (which must necessarily be formed of a material other than manganese
55 steel, which latter cannot be successfully

threaded) from becoming injured or damaged in service, or in any way loosened as it does not come in contact with the material which is being crushed.

With the parts as thus arranged and with 70 the lock nut firmly pressing against the locking ring and mantle, and with the key 25 and pin 27 firmly held in place, the mantle is rigidly and permanently held upon the core. Further, the ratchet-like faces of the 75 locking ring and wearing mantle take advantage of the tendency of the mantle to rotate as soon as it loosens from the core, this tendency to rotation immediately causing the ratchet faces of the ring and mantle 80 to thrust the mantle endwise of the core and wedgedly hold it in proper seated position. The mantle and locking ring, being provided with oppositely inclined faces, provides that this seating action will take 85 place regardless of the direction of rotation of the crusher shaft.

Having thus fully described and explained my invention, I claim and desire to secure by Letters Patent:

90 1. A crusher head comprising a threaded shaft having a rearwardly enlarged core thereon, a manganese steel wearing mantle seating upon said core, a locking ring abutting against the smaller extremity of said mantle, the abutting or confronting surfaces of said locking ring and mantle formed to produce a rearward end pressure upon said mantle upon the relative turning of said locking ring and mantle, the said 95 locking ring being formed of hard wear resisting metal and characterized by a smooth or unthreaded bore extending therethrough, a lock nut engaging said locking ring and holding the external surface of the latter 100 flush with and forming a continuation of the external surface of said mantle, a key engaging the locking ring and lock nut preventing the relative rotation thereof, and a second key engaging the shaft and the 110 locking nut and preventing the relative rotation thereof.

2. A crusher head comprising a threaded shaft having a rearwardly enlarged core thereon, a manganese steel wearing mantle 115 seating upon said core, a manganese steel locking ring abutting against the smaller extremity of said mantle, the abutting or confronting surfaces of said locking ring and mantle formed to produce a rearward 120 end pressure upon said mantle upon the relative turning of said locking ring and mantle, said locking ring provided with a smooth bore extending therethrough and partially formed as an annular recess, a 125 lock nut provided with a protruding shoulder fitting within the annular recess and adapted to support the locking ring with the external surface thereof flushed with and forming a continuation of external sur- 130

face of said mantle, said lock nut sharply bevelled away from the said locking ring, a key engaging the locking ring and lock nut, preventing the relative rotation thereof and a second key engaging the shaft and the lock nut and preventing the relative rotation thereof.

Signed at New York, borough of Man-

hattan, in the county of New York and State of New York, this 20th day of December, A. D. 1920.

FREDERICK H. EDWARDS.
